DRAWING CRAYON OR SIMILAR ARTICLE

Katherine V. Bishop, San Gabriel, Calif.

Application April 5, 1952, Serial No. 19,211

Term of patent 14 years

(Cl. D74—24)

To all whom it may concern:

Be it known that I, Katherine V. Bishop, a citizen of the United States, residing at San Gabriel, in the county of Los Angeles and State of California, have invented a new, original, and ornamental Design for a Drawing Crayon or Similar Article, of which the following is a specification, reference being had to the accompanying drawing, forming a part thereof.

Fig. 1 is a perspective view of a drawing crayon or similar article, showing my new design;

Fig. 2 is a similar view looking toward the opposite side of the crayon as it is viewed in Fig. 1;

Fig. 3 is a side elevational view of the crayon;

Fig. 4 is a similar view disclosing the opposite side of the crayon with respect to that viewed in Fig. 3;

Fig. 5 is an elevational view looking toward one end of the crayon;

Fig. 6 is a similar view looking toward the opposite or pointed end thereof.

I claim:

The ornamental design for a drawing crayon or similar article, substantially as shown.

KATHERINE V. BISHOP.
